UNITED STATES PATENT OFFICE

97,759

DESIGN FOR A FISH BOWL

Samuel J. Carnes, Camden, Ark.

Application July 9, 1935, Serial No. 57,573

Term of patent 3½ years

To all whom it may concern:

Be it known that I, Samuel J. Carnes, a citizen of the United States and a resident of Camden, in the county of Ouachita and State of Arkansas, have invented a new, original, and ornamental Design for a Fish Bowl, of which the following is a specification, reference being had to the accompanying drawing, forming part thereof, in which;

Fig. 1 represents a side elevation of a fish bowl embodying my design.

Fig. 2 represents a front elevation of Fig. 1.

Fig. 3 represents a plan view of Fig. 1.

I claim:

The ornamental design for a fish bowl as shown. In testimony whereof, I affix my signature.

SAMUEL J. CARNES.
